UNITED STATES PATENT OFFICE.

WILLIAM LEACH, OF BRANDON, MANITOBA, CANADA.

MANIFOLD-SHEET FOR BAGGAGE-RECORDS.

932,620.

Specification of Letters Patent. Patented Aug. 31, 1909.

Application filed March 9, 1908, Serial No. 420,073. Renewed June 7, 1909. Serial No. 500,739.

To all whom it may concern:

Be it known that I, WILLIAM LEACH, of Brandon, in the county of Brandon, Province of Manitoba, Dominion of Canada, have 5 invented certain new and useful Improvements in Manifold-Sheets for Baggage-Records, of which the following is a specification.

My invention relates to improvements in 10 manifold sheets for baggage records, and the objects of my invention are to provide a sheet which may be used for a small or large number of entries, and which, when used for a small number may have the used 15 portion detached, leaving the remainder capable of being used again; and it consists essentially of the improved construction hereinafter described in detail, in the accompanying specification and drawings.

20 In the drawings, Figure 1 is a plan view of the sheets on the binder. Fig. 2 is a transverse sectional view.

In the form of sheet shown in Fig. 1, headings *a* and *b* are provided on each end 25 of the sheet reversed in direction with suitable rulings in between, and one or more dividing score lines *c*. By this means if the entries are less than enough to occupy the space to the score line, the portion used may 30 be detached and the sheet reversed and the remaining half used as an original sheet. In case, however, the entries go beyond the score line the complete sheet might be used as if the second heading did not exist.

35 Each manifold sheet consists of two originals *d* and *e* and a duplicating sheet *f* inserted between, which has ruling on each side to correspond with the originals. The three sheets are pasted together along one edge, 40 forming a binding strip *g*, which has perforations therein, through which the binding posts *h* and *i* of a suitable binder extend.

Along the inner edge of the binding strip 45 score lines *j* are provided on both the originals, whereby when filled in, they may be attached. This leaves the binding strip *g* three times the thickness of the duplicating sheet, which is being bound. This gives a 50 desired firmness to the edge of the sheets when they are being permanently placed on file, and enables them to be formed much more readily into a book.

In the system at present in use, the duplicates of the way bills are kept in a book, of which one sheet is devoted to each separate 55 way bill, and so in case there is only one entry a whole sheet of the book must be used up.

It will be seen that my improved sheet, 60 provided with the double headings and dividing score lines, enables the saving of half the number of sheets, where the entries are small, and further, by having the duplicating sheet printed on both sides, each duplicate may serve to give a record of four way 65 bills, where the number of entries are small. This can be done without interfering at all with the efficiency of the system for making out large way bills, as then the bills will not be separated along the score lines. 70

The manifold sheet consisting of the two originals and the duplicate inserted between, with the binding margin at the edge, together forms a sheet which affords great 75 facilities for binding and does away with the necessity of printing the forms in books as at present done.

While I have described with great particularity of detail the invention herein, yet it will be readily understood that changes 80 may be made therein, within the scope of the appended claims without materially departing from the spirit of the invention.

What I claim as my invention is:—

1. A manifold form having reversed headings at opposite ends with a set of rulings extending from one heading to the other and having certain of the ruling lines adapted to serve for either heading. 85

2. A manifold form having reversed headings at opposite ends with a set of rulings extending from one heading to the other and having certain of the ruling lines adapted to serve for either heading, and a medial score line between the two headings. 90

In witness whereof I have hereunto set my hand in the presence of two witnesses.

WILLIAM LEACH.

Witnesses:

A. W. KERR,
S. E. HETHERINGTON.
